(57) CLAIM

I claim the ornamental design for a wine cabinet, as shown and described.

DESCRIPTION

FIG. 1 is a front top left perspective view of a wine cabinet showing my new design,

FIG. 2 is a rear top left perspective view thereof,

FIG. 3 is a front view thereof,

FIG. 4 is a rear view thereof,

FIG. 5 is a right side view thereof,

FIG. 6 is a left side view thereof,

FIG. 7 is a top plan view thereof; and,

FIG. 8 is a bottom view.

The broken lines depict environmental subject matter, are for illustration only, and form no part of the claimed design.
